CALENDAR CLOCK OR SIMILAR ARTICLE

Riki Watanabe, Tokyo-to, Japan, assignor to Kabushiki
Kaisha Koparu, Tokyo-to, Japan

Filed Mar. 22, 1968, Ser. No. 11,095

Term of patent 14 years

Claims priority, application Japan Sept. 29, 1967

Int. Cl. D10—04; D19—03

U.S. Cl. D42—7

FIG. 1

FIG. 2

FIG. 3

FIG. 4

FIG. 1 is a front perspective view of the calendar clock showing my new design;

FIG. 2 is a front elevational view;

FIG. 3 is a rear perspective view; and

FIG. 4 is a left side elevational view.

The dominant features of the design reside in the portions shown in full lines.

I claim:

The ornamental design for a calendar clock or similar article, substantially as shown and described.
